THOMAS A. DE VILBISS, OF TOLEDO, OHIO, ASSIGNOR TO THE DE VILBISS COMPANY,
OF TOLEDO, OHIO, A CORPORATION OF OHIO

ATOMIZER

Application filed January 3, 1928. Serial No. 244,144.

This invention relates to an atomizer especially adapted to be used in connection with toilet articles which contain perfume or the like. Its object is primarily to provide a device of this kind which is simple in construction and in which special provision is made to prevent the escape of the contents of the container when it is not in use.

In atomizers of this kind, as heretofore generally constructed, it has been thought necessary, or at least desirable, to provide a small vent in the stopper to prevent the liquid contents of the container from bubbling over by reason of the evaporation and resultant expansion of the gas within the container. Even then the vent, which is of course quite small, often gets stopped up and the liquid, which contains alcohol, runs out and causes considerable damage to the finish of the dresser or table upon which the atomizer is kept.

It should also be borne in mind that open vent holes permit the gradual escape of a considerable part of the volatile contents of the container. This is wasteful and the strength of the perfumery or other preparation in the container is much weakened. Atomizers have been made in which cut-offs were provided for the nozzle and vent, but these are complicated and expensive and are not very convenient.

The present invention has been perfected with the object of overcoming the above mentioned difficulties. In its preferred form, it comprises a small cup, which provides a liquid seal for both the air inlet and the nozzle, yet the capacity of the cup is so small that a vent is unnecessary, since the few drops contained therein may bubble over without causing any damage. This cup is preferably arranged in such a manner that it may be adjusted to cut off the air inlet and nozzle completely, thus making it possible to pack the container with its contents in a travelling bag or the like, without any danger of spilling the contents.

The specific construction of the invention, and its mode of operation, will be more particularly described in connection with the accompanying drawing, in which :

Figure 1 is a central vertical sectional view of the invention in position for operation.

Fig. 2 is a similar view illustrating another adaptation of the invention.

The invention is illustrated in connection with a container 5 of conventional design and provided with a mouth 6 permanently secured thereto in any suitable manner and composed of rust proof metal or some material having similar properties. Various types or styles of stoppers may be used for the container as represented at 7 and 8 in Figures 1 and 2, respectively. These stoppers have screw threaded connections with the mouth of the container, the latter being provided with a seat for receiving a packing ring 9. In the form shown in Figure 1, the stopper 7 has a head 10 permanently secured to its upper end and formed with a nozzle 11 having a small outlet 12 located centrally thereof. The head 10 is formed with a small air passageway 13 in alignment with the outlet 12 and a tube 14 is secured at one end in the head 10 with its bore 15 in communication with the passageway 13. A bulb 16 secured to the other end of the tube 14 is adapted to force air under pressure through the passageway 13 and nozzle outlet 12.

The head 10 is formed with a second passageway 17 leading into the nozzle 11 and connected with a bore 18 formed in the stopper 7. A small cup 19 is adapted to be connected to the stopper 7 and to be received within the upper part of the container 5. The cup 19 has a central stem 20 extending upwardly from its bottom and beyond the rim of the cup where it is threaded as at 21 for connection with the correspondingly threaded portion of the stopper 7. The stem 20 has a central bore 22 in alignment with the bore 18 in the stopper and adapted to receive the contents of the cup 19 through a port 23 at its lower end.

The side wall 24 of the cup has its rim beveled as at 25 and is adapted to fit tightly against a correspondingly shaped seat 26 formed in the bottom of the stopper, when the stem 20 is screwed into the stopper as far as possible.

In the modification shown in Figure 2, the

parts of the cup 19 and other parts which are similar to those shown in Figure 1 are designated by the same reference characters. A nozzle 27 is secured in the stopper 8 and is formed with an outlet 28. The nozzle 27, however, is not in direct communication with the tube 14. The nozzle 27 has an inner member 29 which is in alignment with the outlet 28 and connects the same with the bore 18 in the stopper. The inner member 29 of the nozzle 27 is surrounded by a space 30 which is connected with the interior of the cup 19 by a passageway 31. The tube 14 is connected to the interior of the cup by a passageway 32.

When the atomizer is in position for use, the cup 19 will be adjusted to the position shown in the drawing with the beveled rim 25 spaced from the seat 26. Liquid from the container 5 may be caused to flow into the cup by shaking or tilting the container. In the operation of the atomizer as shown in Figure 1, when the bulb 16 is compressed, air will be forced under pressure through the passageway 13 and nozzle outlet 12. This will cause a suction in the passageway 17 and the bore 18 of the stopper and will cause liquid to be drawn from the cup 19 and mixed with the air emitted from the outlet 12 so as to form a fine mist or spray.

When the atomizer is not in use, if a small amount of liquid is left in the cup 19 to cover the port 23, this will form a liquid seal to prevent evaporation of the contents of the container. It will be understood of course that the area of the bore 22 is so small that evaporation therefrom will be practically negligible. If the pressure within the container 5, due to heat or other causes, should become great enough to force the contents of the cup 19 through the nozzle, the amount of the same will be so small that it will cause no damage, and after the cup has been emptied there will be a free vent through the port 23.

When the atomizer is to be packed for travelling, the cup 19 will be screwed tightly against the seat 26 so that it will be impossible for the contents of the container to be spilled.

In the form shown in Figure 2, the structure and the function of the cup 19 are substantially the same as in the form shown in Figure 1. Fig. 2, however, shows a different type of atomizer in which pressure acts directly on the liquid to force the same through the nozzle. When the bulb 16 is compressed, air is forced under pressure into the cup 19. At the same time, the air pressure against the surface of the liquid forces the latter through the port 23 and upwardly through the bore 22 and through the inner portion 29 of the nozzle. The increase in air pressure causes a current of air under pressure to pass through the bore 31 and through the outer portion

of the nozzle. These streams of air and liquid will become mixed and will be emitted from the outlet 28 in the form of a fine spray or mist.

From the foregoing description it will be understood that the invention is adapted to be used on any type of atomizer and is especially desirable in preventing any possibility of damage to the dresser or table on which it is kept. At the same time it prevents waste of the contents of the container without the use of any complicated or expensive mechanism. It is apparent also that the structure shown in the drawing is merely for the purpose of illustration and that the same may be considerably modified without any material departure from the scope of the invention as claimed.

What I claim is:

1. In an atomizer, the combination with a container and a stopper therefor having a passageway through which liquid may be discharged, of a cup supported in position to constitute a liquid seal for said passageway when the cup contains the requisite amount of liquid, said cup being adjustable to effect a closure between the contents of the container and said passageway to prevent escape of said contents.

2. In an atomizer, the combination with a container and a stopper therefor having a passageway through which liquid may be discharged, of a hollow stem constituting a downward extension of said passageway and a cup supported by the stem in position to constitute a liquid seal for said passageway when the cup contains the requisite amount of liquid, said stem having an inlet port within the cup near the bottom thereof, said stem being adjustable to raise the cup and effect a closure between the contents of the container and said passageway to prevent escape of said contents.

3. The combination with a liquid container, of a stopper having a liquid passageway therethrough, and means depending from said stopper for receiving a small portion of the liquid contents of the container, when the container is shaken, and covering the lower end of said passageway therewith.

4. The combination with a liquid container, of a stopper having a liquid passageway therethrough, and means for receiving a small portion of the liquid contents of the container, when the container is shaken, and covering the lower end of said passageway therewith, said means being adjustable to effect a closure between the contents of the container and said passageway to prevent escape of said contents.

5. A stopper for liquid containers and having a liquid passageway therethrough, a cup having a stem connected with the stopper and a rim encompassing said stem and spaced therefrom, said stem being adjustable

to cause the rim of the cup to engage the stopper, the bottom of said stopper being formed with a seat surrounding said passageway, against which said rim is engageable to form a liquid tight closure.

6. A stopper for liquid containers and having a liquid passageway therethrough, a cup having a hollow stem connected with the stopper, said stem constituting a downward extension of said passageway and having an inlet port within the cup near the bottom thereof, said cup being adapted to receive liquid from the container to cover said port, said stem being adjustable to cause the rim of the cup to engage the stopper, the bottom of said stopper being formed with a seat surrounding said passageway, against which said rim is engageable to form a liquid tight closure.

7. A stopper for liquid containers and having a liquid passageway therethrough, a cup having a hollow stem extending upwardly from its bottom, said hollow stem having a threaded connection with the stopper and constituting the inlet end of said passageway, said stem being adjustable to cause the rim of the cup to engage the stopper, the bottom of the stopper being formed with a seat against which said rim engages to form a liquid tight closure.

8. In an atomizer, the combination with a container and a stopper therefor, of a cup, means for supporting the cup in open position within the container, a nozzle, means for discharging liquid from the cup through the nozzle, and means to adjust the cup and seat its rim against the stopper, thereby effecting a closure for the cup and positively excluding the contents of the container from the cup and from the nozzle.

9. In an atomizer, the combination with a container and a stopper therefor having a passageway through which liquid may be discharged, of a cup supported beneath the entrance to said passageway and having a rim encompassing said entrance and normally spaced from the stopper, said cup being adjustable to seat its rim against the stopper and effect a closure between the contents of the container and the interior of said cup and passageway to prevent escape of said contents.

10. In an atomizer, the combination with a container and a stopper therefor having a passageway through which liquid may be discharged, of a cup supported beneath said passageway in position to constitute a liquid seal therefor when the cup contains sufficient liquid, there being normally free communication over the rim of the cup between the interior thereof and the rest of the space inside the container, whereby liquid may be transferred from the latter to the cup by shaking or tilting.

11. In an atomizer, the combination with

a container and a stopper therefor having a passageway through which liquid may be discharged, of a cup supported beneath said passageway and having a hollow stem constituting an extension thereof, said stem having an inlet port within the cup near the bottom thereof, said cup being normally in such position that there is free communication over its rim between the interior of the cup and the rest of the space inside the container, whereby liquid may be transferred from the latter to the cup by shaking or tilting.

12. The combination with a liquid container, of a stopper having a liquid passageway therethrough, means for receiving a small portion of the liquid contents of the container when the container is shaken or tilted, and covering the lower end of said passageway therewith, and a central stem connected to said stopper and supporting said receiving means.

13. The combination with a liquid container of a stopper having a liquid passageway therethrough, means for receiving a small portion of the liquid contents of the container when the container is shaken or tilted and effecting therewith a liquid seal for the lower end of said passageway, a stem connected to said stopper and supporting said receiving means, said stem having a prolongation of the passageway through the stopper.

14. A stopper for liquid containers and having a liquid passageway therethrough, a cup having a stem connected with the stopper and a rim encompassing said stem and spaced therefrom, said stem being adjustable to cause the rim of the cup to seat against the bottom of the stopper to form a liquid tight closure, said stem being formed with a passageway constituting a prolongation of the passageway through the stopper and having an inlet opening from the interior of the cup.

In testimony whereof, I have hereunto signed my name to this specification.
